(57) **CLAIM**

The ornamental design for a store facade, as shown and described.

DESCRIPTION

FIG. 1 is a perspective view of a store facade as shown in the drawings;

FIG. 2 is a front elevation view of the store facade of FIG. 1;

FIG. 3 is a rear elevation view of the store facade of FIG. 1;

FIG. 4 is a left side view of the store facade of FIG. 1;

FIG. 5 is a right side view of the store facade of FIG. 1;

FIG. 6 is a top plan view of the store facade of FIG. 1; and,

FIG. 7 is a bottom plan view of the store facade of FIG. 1. The store name is shown in broken lines to depict environment only that forms no part of the claimed design.
